US00D919461S

(12) **United States Design Patent** (10) **Patent No.:** **US D919,461 S**
(45) **Date of Patent:** **** May 18, 2021**

(54) **SENSOR COMPONENT COVER**

(71) Applicant: **Lyft, Inc.**, San Francisco, CA (US)

(72) Inventors: **Alfred Charles Jones, II**, San Jose, CA (US); **Eric Daniel Fields**, Oakland, CA (US); **Steve Chen**, Milpitas, CA (US); **David Bearn DeVore**, Daly City, CA (US); **Steven Son Khau**, Belmont, CA (US); **David Timothy Milton**, San Jose, CA (US)

(73) Assignee: **Lyft, Inc.**, San Francisco, CA (US)

(**) Term: **15 Years**

(21) Appl. No.: **29/696,684**

(22) Filed: **Jun. 28, 2019**

(51) LOC (13) Cl. **10-04**

(52) U.S. Cl.

USPC **D10/70; D12/400**

(57) **CLAIM**

The ornamental design for a sensor component cover, as shown and described.

DESCRIPTION

FIG. 1 is a perspective view of a sensor component cover, illustrating a new design.

FIG. 2 is a front view thereof.

FIG. 3 is a rear view thereof.

FIG. 4 is a left view thereof.

FIG. 5 is a right view thereof.

FIG. 6 is a top view thereof.

FIG. 7 is a bottom view thereof.

FIG. 8 is a rear perspective view thereof.

FIG. 9 is an enlarged top, right perspective view thereof shown with a portion of a vehicle, in an exemplary use.

FIG. 10 is a top, right perspective view thereof shown with a top, right perspective view of a vehicle, in an exemplary use.

FIG. 11 is a right, side view thereof shown with a right, side view of a vehicle, in an exemplary use.

FIG. 12 is a top view thereof shown with a top view of a vehicle, in an exemplary use; and,

FIG. 13 is a front view thereof shown with a front view of a vehicle, in an exemplary use.

Illustrations in broken lines in FIGS. 1–8 depict portions of the sensor component cover that form no part of the claimed design. Illustrations in broken lines in FIGS. 9–13 depict a vehicle environmental structure that forms no part of the claimed design. The broken lines illustrating symbolic break lines in FIG. 9 form no part of the claimed design.

1 Claim, 13 Drawing Sheets
